STORAGE TANK

Robert W. Bodley, Highland, Ind., assignor to Union Tank Car Company, Chicago, Ill., a corporation of New Jersey

Filed Sept. 27, 1961, Ser. No. 141,110
14 Claims. (Cl. 220—26)

The present invention relates to storage tanks of the fixed and floating roof type and, more particularly, relates to a storage tank that is capable of venting to the atmosphere vapors which have formed beneath the floating roof.

Fixed roof or closed roof storage tanks embodying floating roofs are well known in the art. Although the floating roof rests or floats upon the stored liquid to prevent its volatilization, there are periods during normal operation of these tanks when it is impossible for the floating roof to rest upon the liquid. Two such periods, for example, are when the tank is being filled for the first time (start-up) and when it is being filled after having been cleaned. During these periods vapor formation cannot be avoided.

It has been the practice in the past to vent vapors formed during these periods through the floating roof into the zone between the fixed roof and the floating roof. Though this effectively removed the vapors from beneath the floating roof, it may create an explosive mixture of vapor and air in this zone which, if ignited, would cause complete destruction of the tank and loss of the stored liquid. Thus this practice created hazardous operating conditions.

It is therefore an object of the instant invention to provide an improved storage tank embodying both a cone or fixed roof and a floating roof.

It is another object of the instant invention to provide storage tanks containing floating roofs wherein vapors formed beneath the floating roof are vented directly to the atmosphere, thereby precluding hazardous operating conditions.

It is a further object in accordance with the previous object to vent the vapors to the atmosphere without the vapors entering the zone between the floating and fixed roofs of the tank.

It is a further object of the instant invention to provide in a storage tank a ventilating arrangement that is integrated with the structure ordinarily required in storage tank constructions whereby the ventilating feature is provided at relatively small additional expense.

It is a further object of the instant invention to provide in a storage tank a venting arrangement associated with a ladder or a support column for the fixed roof to exhaust to the atmosphere vapors formed beneath its floating roof, the fluid and vapors being prevented from passing into the zone of the tank above the floating roof by the gas-tight relationship existing between the floating roof and the ladder or support column arrangement.

The above and other objects are realized in accordance with the present invention by providing a new and improved storage tank of the type embodying both a fixed cone roof and a floating roof. The storage tank includes a ventilating arrangement that vents vapors formed beneath the floating roof directly to the atmosphere without passing through the zone between the floating and fixed roofs. The ventilating arrangement preferably is integrated with structure conventionally embodied in storage tanks, for example, the access ladder or the support column for the fixed roof. Specifically, the ladder or support column between the exterior of the tank and the interior of the tank provides communication below the floating roof when it is in its start-up and cleaning posi-

2

tions. The floating roof and ladder or support column are in gas-tight relation.

The invention, both as to its organization and method of operation, taken with further objects and advantages thereof, will best be understood by reference to the following description taken in conjunction with the accompanying drawings, in which:

FIG. 1 is a cross-sectional view of a storage tank embodying the features of the present invention, illustrating the floating roof in its cleaning position;

FIG. 2 is a fragmentary top plan view of the storage tank of FIG. 1 taken along lines 2—2;

FIG. 3 is a fragmentary cross-sectional view taken along lines 3—3 of FIG. 1;

FIG. 4 is a fragmentary cross-sectional view of the storage tank of FIG. 1, illustrating the floating roof in its start-up position;

FIG. 5 is an enlarged fragmentary cross-sectional view of an embodiment of the storage tank of FIG. 1, illustrating the floating roof and associated ladder construction; and

FIG. 6 is an enlarged perspective view of the sealing means shown in FIG. 5.

Referring now to the drawings, and more particularly to FIGS. 1—4, there is illustrated a closed storage tank of the floating-roof type identified generally by reference numeral 10. The storage tank 10 serves to store liquid, for example, petroleum products, which is fed to and withdrawn from the tank 10 through suitable conduits and valving arrangements (not shown) which communicate with the lower portion of the tank 10.

The tank 10 includes a circular floor 12 which is located on the ground and a generally cylindrical shell 16 extending upwardly from the periphery of the floor 12. The shell 16 supports the edge of a fixed roof 18 that has an upwardly extending conical shape. In addition to the shell 16, vertical columns (not shown) extending upwardly from the floor 12 may be employed to internally support the fixed roof 18.

To provide access to the interior of the tank 10 a ladder, identified generally by reference numeral 22, is secured to the floor 12 and extends upwardly therefrom through the fixed roof 18 so that its upper end is adjacent to a conventional manway 24 (see FIG. 2).

To prevent volatilization of the liquid stored in tank 10, a floating roof, identified generally by reference numeral 28, floats on and extends over substantially the entire surface of the liquid. As is known to those skilled in the art, the floating roof 28 moves vertically within the storage tank 10 as the level of the liquid within the tank 10 changes. To prevent vapor loss, a suitable sealing arrangement 11 of the type disclosed and claimed in an application Serial No. 821,247, filed by Reign C. Ulm, on June 18, 1959, which issued as United States Patent No. 3,154,213 on October 27, 1964, and assigned to the same assignee as the present invention, is supported by the floating roof 28 so as to frictionally engage the shell 16, irrespective of the position of the floating roof 28 within the tank 10. The floating roof 28 is suitably apertured at 30 and 13 to accommodate the ladder 22 and the adjustable support members 41, respectively.

The construction of the floating roof 28 in general is immaterial to the instant invention and the illustrated construction is merely exemplary. The floating roof 28 in FIG. 1 is of the type disclosed and claimed in an application Serial No. 122,497, filed by Robert W. Bodley, on July 7, 1961, which issued as United States Patent No. 3,134,501 on May 26, 1964, and assigned to the same assignee as the present invention. It may comprise a plurality of flanged sections which have been secured together at joints, indicated generally by reference nu-

65
70

meral 39, to form a substantially continuous bottom surface 38 which rests upon the liquid stored in the tank. An upwardly extending L-shaped flange 40 is positioned around the periphery of the floating roof 28. The sealing arrangement 11 is secured to the vertically disposed leg of the L-shaped flange 40. The horizontally disposed leg of L-shaped flange 40 has openings therein adapted to engage the adjustable support means 41, a plurality of which are disposed around the periphery of the floating roof.

Supporting the floating roof 28 above floor 12 during the start-up and cleaning operations, which will be discussed in more detail hereinafter, are adjustable support means 41, which comprise a sleeve member 42 which extends through the flange 40 and the hole 13 in roof bottom 38. Sleeve member 42 is secured to the floating roof by welding or the like and is adapted to slidably receive a pipe-like supporting leg 43, which has transverse holes 48 (see FIG. 4) and 48a therein at different levels for reasons apparent hereinafter. Sleeve 42 has a pair of aligned transverse holes. Thus when hole 48 in supporting leg 43 is aligned with the holes in sleeve 42, a large pin 44 may be inserted through the aligned holes to rigidly position the supporting leg 43 as shown in FIGURE 1. Support legs 43 of adjustable support means 41 rest upon pads 49 when they support the floating roof.

Extending upwardly from the floating roof around the periphery of the opening 30, through which ladder 22 extends, is an inverted L-shaped flange 45. A sealing means 46, which prevents vapor and fluid from entering the zone within the tank above the floating roof, is secured by suitable means, such as nuts and bolts or screws, to the annular, horizontally disposed leg of flange 45. As shown in FIG. 3 sealing means 46 contains an opening or slot which conforms to the horizontal cross-sectional configuration of ladder 22, i.e., two circular-shaped openings connected by a long rectangular-shaped slot. The opening is slightly, proportionally smaller than the cross-sectional dimensions of the ladder 22 so that a tight seal is effected between the seal and ladder. Sealing means 46 prevents vapor and fluid from flowing through passageway 30 to the other side of floating roof 28. Sealing means 46 is made of rubber, plastic, fabric or other suitable flexible, gas impervious material.

Considering now in more detail the venting arrangement of the instant invention wherein vapors beneath the roof are exhausted directly to the atmosphere, the ladder 22 comprises a pair of spaced, upright, hollow side rails 31 and 32 interconnected by a plurality of rungs 33. The ladder 22 extends through the floating roof 28 and is secured to the floor 12 of the tank 10. The rails 31 and 32 are hollow and form the venting passageways which communicate with the interior of the tank through openings 34 and 35, respectively, in the rails. The venting passageways in rails 31 and 32 communicate with the outside of the tank through openings 26 and 27, respectively, at the uppermost ends of the rails. Vent caps 37 are securely positioned above these openings to prevent foreign matter from entering the storage tank 10.

Having described the apparatus, its operation will be understood from the following discussion. FIG. 4 illustrates the floating roof as it appears during the start-up operation; that is, when it is being filled for the first time. During start-up the floating roof must be supported above the floor, since the liquid to be stored must have room to enter the storage tank beneath the floating roof. In the instant illustrated apparatus, the floating roof is supported about 3 feet above floor 12 by support legs 43 which are secured to sleeve 42 by means of pin 44 extending through the holes in sleeve 42 and hole 48a in support leg 43. Liquid to be stored in the storage tank is fed by suitable means (not shown) into the tank below the floating roof. During this start-up operation there will obviously be a period of time in which the floating roof will not rest upon the liquid in the storage tank. As a result, vapors will form between the liquid and floating roof. If this

vapor is not removed the floating roof will rise on the vapor, rather than on the liquid as desired.

As explained hereinbefore, in prior art floating roof constructions there were provided means for venting this vapor from below the floating roof to the zone between the floating roof and the fixed roof of the storage tank. This was undesirable as it created a combustible mixture of vapor and air in this zone.

In the instant invention, however, this problem during start-up is avoided by means of the venting passageway and opening 35 in the rail 32 of ladder 22. While the liquid is being passed into the storage tank below the floating roof 28, any vapor which is formed is vented through opening 35 and the venting passageway in rail 32 to the atmosphere. Thus by the time the entering liquid has reached the level of the floating roof shown in FIG. 4, all the vapor has been expelled from beneath the floating roof through the venting passageway to the atmosphere and the roof will rise on the level of the liquid, rather than on vapor above the liquid. Once the floating roof begins to rise it may, of course, ascend substantially to the top of storage tank 10 depending on the level of the liquid stored.

In the instant embodiment, opening 35 is positioned such that when the floating roof is in its start-up position it is between the sealing means 46 and the level of the floor bottom 38 of roof 28. It will be understood, however, that though this is the preferred position of this opening, it will suffice if any portion of the opening 35 is above the bottom level 38 of roof 28. In this manner all of the vapor formed below the floating roof may be expelled to the atmosphere while simultaneously sealing off the zones below and above the floating roof.

Periodically the tank must be cleaned. This may be occasioned by the use of the tank to store a different liquid or merely to remove sediment or the like formed during continued storage of similar materials. To prepare the tank for cleaning, a workman, prior to removing the liquid from the tank, will adjust support members 41 to their cleaning position. This requires the workman to enter the tank via manway 24 and ladder 22 and get on the top of floating roof 28. There he adjusts each support means 41 (which are in the start-up position) by removing pin 44 and lowering pipe 43 in sleeve 42 such that hole 48 is in line with the holes in sleeve 42. The pin 44 is then inserted through the aligned holes and the support means is in the cleaning position. Thus as the liquid is drained from the storage tank 10 the adjustable support legs 43 will come to rest upon pads 49 and support the floating roof about six feet from the floor 12 of the tank as shown in FIG. 1. After all the liquid has been removed from the storage tank 10 a man or men may enter tank 10 via manholes (not shown) located below the floating roof and clean the floor and the walls of the tank.

When the tank is being filled after a cleaning operation there will be a period of time in which vapor may form between the liquid and the floating roof. However, the opening 34 in rail 31 permits the vapor to pass via the venting passageway to the atmosphere. As illustrated, opening 34 is positioned such that when the floating roof is in its cleaning position it is between the sealing means 46 and the level of the floor bottom 38 of roof 28. It will be understood, however, that though this is the preferred position of this opening, it suffices if any portion of opening 34 is above the bottom level 38 of roof 28. In this manner all of the vapor formed below the floating roof may be expelled while simultaneously sealing off the zones below and above the floating roof. Opening 34 and the venting passageways in rail 31 therefore operate in the same manner after cleaning as opening 35 and the venting passageway in rail 32 operate during start-up.

Once the floating roof begins to rise on the liquid, generally a workman will enter the storage tank and place the supporting legs in their start-up position. The tank is then ready for normal operation. That is the

liquid level may fluctuate between substantially the height of the storage tank to about three feet above the floor of the tank and the floating roof will at all times during such fluctuations rest upon the liquid.

Referring now to FIGS. 5 and 6 there is shown a modified sealing means to prevent vapor or liquid from flowing through an opening 60 in floating roof 28 through which the venting ladder 22 extends. The sealing means, indicated generally by reference numeral 70, comprises two mating members 71 and 72 which have vertical members 75 having surfaces which conform generally to the contour of the side of the ladder 22. Each vertical member 75 is connected to a horizontally disposed lip 77 which has a pair of vertical, laterally extending flanges 74. Each vertical member 75 has a pair of longitudinal, vertically disposed flanges 76. The two mating members 71 and 72 are placed around ladder 22 above the floating roof 28 and secured together by means of nuts and bolts or the like (not shown) which extend through suitable holes in flanges 76 and 74. Suitable rubber or plastic gaskets 78 are placed between the flanges 76 and 74 prior to securing the mating members 71 and 72 together.

The floating roof 28 has an L-shaped flange 61 which extends upwardly around the periphery of the opening 60. Its horizontally disposed, annular surface 62 will seat the sealing means 70 which is slidably mounted around ladder 22. A suitable rubber or plastic gasket 63 is secured to the upper surface of leg 62 to insure a good seal between sealing means 70 and the annular surface 62.

Referring now specifically to FIG. 5 the floating roof and sealing means are shown as they would appear when the floating roof is in its clean-up position, i.e., in the same position shown in FIG. 1. The dotted lines in FIG. 5 indicate the position of the floating roof and sealing means when the floating roof is in its start-up position, i.e., the same position shown in FIG. 4. Basically the operation of the venting system and floating roof discussed hereinbefore is applicable to the instant embodiment, the only distinction being that sealing means 70 rides upon surface 62 of flange 61 and is maintained in that position merely by its own weight without the necessity for any physical attachment between the sealing means and this flange. In addition it will be noted that openings 80 and 90 in the rails are positioned to communicate with the tank below the floating roof 28 when it is in its cleaning and start-up position, respectively, and extend upwardly slightly above the bottom level of the floating roof 28 when it is in these positions to compensate for liquid displacement caused by the weight of the roof 28. In this manner, all the vapor formed below the floating roof may be expelled prior to the roof 28 beginning to float.

Though the instant venting arrangement has been illustrated and described in conjunction with a ladder in the storage tank, it will be understood that it may also be effected through the vertical, hollow supporting columns employed to give additional support to the fixed roof of the storage tank. In that instance the vertical support column would extend through the fixed roof and open to the atmosphere as do the rails of the ladder discussed hereinbefore. One column may effect venting in both the situations discussed hereinbefore by having two appropriately positioned openings therein. In the alternative, venting may be effected by two supporting columns, one column effecting venting during start-up and the other effecting venting as the tank is being filled after cleaning. In all other respects the sealing means, vent caps and the like would be similar with the exception that they would be adapted to receive and cooperate with the venting support columns rather than the ladder.

Furthermore, it will be understood that the various venting arrangements described herein also will allow air from outside the tank to enter between the floating roof and the liquid while the tank is being emptied after

the floating roof is resting in its cleaning or start-up position. In this manner, a partial vacuum beneath the floating roof 28 may not be formed.

While several embodiments described herein are at present considered to be preferred, it is understood that various modifications and improvements may be made therein, and it is intended to cover in the appended claims all such modifications and improvements as fall within the true spirit and scope of the invention.

10 What is desired to be claimed and secured by Letters Patent of the United States is:

1. A closed storage tank containing a floating roof therein and means for venting to the atmosphere vapors formed beneath said floating roof, said means comprising a substantially vertical member positioned within said tank and extending to the bottom of said tank, said vertical member extending through an opening in said floating roof, said vertical member having a venting passageway therein which communicates with the atmosphere and with said tank below said floating roof, and sealing means cooperating with said floating roof and said vertical member to prevent the flow of vapors from beneath said floating roof to the top of said floating roof, said sealing means comprising an elongate vertical sealing member having an opening therein which is adapted to slidably receive said vertical member, said sealing member being adapted to be non-attachably seated upon said floating roof around the periphery of said opening in said floating roof through which said vertical member extends, said sealing member comprising two mating members which are connected around said vertical members and adapted to slide vertically upon said vertical member with the movement of said floating roof.

2. A closed storage tank containing a floating roof therein having a start-up position and a higher cleaning position and means for venting to the atmosphere vapors formed beneath the floating roof as said storage tank is being filled during start-up and after cleaning, said means comprising a ladder vertically positioned within said tank, said ladder having a first and second rail each having a venting passageway therein, said venting passageways communicating with the exterior of said tank, one of said passageways communicating with the interior of said tank through an opening in said first rail located below the floating roof when said floating roof is in the start-up position and said other venting passageway communicating with the interior of the tank through an opening in said second rail located above the opening in said first rail and below the level of said floating roof when said floating roof is in the cleaning position.

3. The storage tank of claim 2 wherein at least a portion of said opening in said first rail is located above the bottom of said floating roof when said floating roof is in the start-up position.

4. The storage tank of claim 2 wherein at least a portion of said opening in said second rail is located above the bottom of said floating roof when said floating roof is in the cleaning position.

5. A closed storage tank containing a floating roof therein and means for venting to the atmosphere vapors formed beneath said floating roof, said means comprising a ladder vertically positioned within said tank and extending to the bottom of said tank, said ladder extending through an opening in said floating roof, said ladder having a venting passageway therein which communicates with the atmosphere and with said tank below said floating roof, and sealing means cooperating with said floating roof and said ladder to prevent the flow of vapor from beneath said floating roof to the top of said floating roof.

6. A closed storage tank containing a floating roof therein and means for venting to the atmosphere vapors formed beneath said floating roof, said means comprising a ladder vertically positioned within said tank and extending to the bottom of said tank, said ladder extending through an opening in said floating roof, said ladder

having a venting passageway therein which communicates with the atmosphere and with said tank below said floating roof, and sealing means cooperating with said floating roof and said ladder to prevent the flow of vapor from beneath said floating roof to the top of said floating roof, said sealing means comprising a flexible member secured to said floating roof, and having an opening therein which conforms substantially to the cross-sectional configuration of the ladder, said ladder extending through said opening in said flexible member.

7. A closed storage tank containing a floating roof therein and means for venting to the atmosphere vapors formed beneath said floating roof, said means comprising a ladder vertically positioned within said tank and extending to the bottom of said tank, said ladder extending through an opening in said floating roof, said ladder having a venting passageway therein which communicates with the atmosphere and with said tank below said floating roof, and sealing means cooperating with said floating roof and said ladder to prevent the flow of vapor from beneath said floating roof to the top of said floating roof, said sealing means comprising an elongate member having an opening therein which is adapted to slidably receive said ladder, said sealing means being adapted to be seated upon said floating roof around the periphery of said opening in said floating roof through which said ladder extends.

8. The storage tank of claim 7 wherein said sealing member comprises two mating members which are connected around said ladder and adapted to slide vertically upon said ladder with the movement of said floating roof.

9. A closed storage tank containing a floating roof therein and means for venting to the atmosphere vapors formed beneath said floating roof, said means comprising a ladder vertically positioned within said tank and extending to the bottom of said tank, said ladder extending through an opening in said floating roof, said ladder having a venting passageway therein which communicates with the atmosphere and with said tank below said floating roof, and sealing means cooperating with said floating roof and said ladder to prevent the flow of vapor from beneath said floating roof to the top of said floating roof, said sealing means comprising two elongate members having vertical surfaces which conform to the side configuration of said ladder, said elongate members being connected together around said ladder with said vertical surfaces in slidable contact with said ladder, said elongate members having flanges adapted to rest upon said floating roof around the periphery of the opening in said floating roof through which the ladder extends.

10. The storage tank of claim 9 wherein said floating roof has a flange extending upwardly around the periphery of the opening in said floating roof for said ladder, said flange containing a horizontally disposed leg, said sealing means being seated upon said horizontally disposed leg of said flange, and a gasket means between said horizontally disposed flange and said sealing means.

11. A closed storage tank containing a floating roof therein having a start-up position and a higher cleaning position and means for venting to the atmosphere vapors formed beneath the floating roof as said storage tank is being filled during start-up and after cleaning, said means comprising a ladder vertically positioned within said tank, said ladder having a first and second rail each having a venting passageway therein, said venting passageways communicating with the exterior of said tank, one of said passageways communicating with the interior of said tank through an opening in said first rail located below the floating roof when said floating roof is in the start-up position and said other passageway communicating with the interior of the tank through an opening in said second rail located above the opening in said first rail and below the level of said floating roof when said floating roof is in the cleaning position, and sealing means cooperating with said ladder and said floating roof to prevent vapor from flowing between said ladder and said floating roof to the top of said floating roof.

12. The storage tank of claim 11 wherein said floating roof has an opening therein through which said ladder extends, said roof having an upwardly extending flange around the periphery of said opening, said sealing means being secured to said flange, at least a portion of said opening in said first rail being located above the bottom of said floating roof when said floating roof is in the start-up position and at least a portion of said opening in said second rail being located above the bottom of said floating roof when said floating roof is in the cleaning position.

13. The storage tank of claim 12 wherein said sealing means comprises a flexible member having an opening therein which conforms to the cross-sectional configuration of said ladder, said ladder extending through said opening in said flexible member.

14. The storage tank of claim 13 wherein said opening in said first rail is between the level of the bottom of said floating roof and said sealing means when said floating roof is in the start-up position and said opening in said second rail is between the level of the bottom of said floating roof and said sealing means when said floating roof is in the cleaning position.
